(57) **CLAIM**

The ornamental design for a can dispenser, as shown and described.

DESCRIPTION

FIG. 1 is a frontal isometric view of my new can dispenser;

FIG. 2 is a rear isometric view thereof;

FIG. 3 is a front elevational view;

FIG. 4 is a rear elevational view;

FIG. 5 is a right end elevational view;

FIG. 6 is a left end elevational view;

FIG. 7 is a top plan view;

FIG. 8 is a bottom plan view; and,

FIG. 9 is a frontal isometric view of the can dispenser thereof, the broken-line disclosure of cans and tops being for illustrative purposes only and forming no part of the claimed design.
